UNITED STATES PATENT OFFICE.

GEORGE HOEPNER, OF CHICAGO, ILLINOIS.

THREAD-CUTTER FOR SEWING-MACHINES.

1,263,766.

Specification of Letters Patent. Patented Apr. 23, 1918.

Original application filed October 29, 1916, Serial No. 128,104. Divided and this application filed August 15, 1917. Serial No. 186,253.

To all whom it may concern:

Be it known that I, GEORGE HOEPNER, a citizen of the United States, residing at Chicago, county of Cook, State of Illinois, have invented a certain new and useful Improvement in Thread-Cutters for Sewing-Machines, and declare the following to be a full, clear, and exact description of the same, such as will enable others skilled in the art 10 to which it pertains to make and use the same, reference being had to the accompanying drawings, which form a part of this specification.

My invention has for its object to produce 15 a simple, novel and efficient attachment for a sewing machine by means of which the thread may be quickly and conveniently cut after a seam has been made.

The various features of novelty whereby 20 my invention is characterized will herein-after be pointed out with particularity in the claims; but, for a full understanding of my invention and of its object and advantages, reference may be had to the following 25 detailed description taken in connection with the accompanying drawing, wherein:

Figure 1 is a side elevation of my improved cutting device and fragments of the frame of a sewing machine to which the 30 device is attached;

Fig. 2 is a side view of the tubular member of the cutter;

Fig. 3 is an end view looking at the right hand end of Fig. 2;

Fig. 4 is a side view of the rotatable member of the cutter; and

Fig. 5 is an end view looking at the right hand end of Fig. 4.

My invention is applicable to sewing machines of any type, but may be used to particular advantage in connection with machines adapted for heavy service such, for example, as bag sewing machines of the type illustrated in my application for sewing machine, filed October 29, 1916, Serial No. 128,104, of which the present application is a division.

The cutter comprises a stationary member, 1, in the form of a short tube having in one end a notch, 2, which, in the arrangement illustrated, is V-shaped; and having in the same end and diametrically opposed to the notch 2, a second notch, 3, which, in the arrangement shown, is broader and deeper 55 than the other notch. Revoluble within the

tubular member 1 is a shaft, 4, forming the rotatable member of the cutter, the shaft preferably fitting nicely into the tube so that there will be no lateral play. One end of the shaft extends to the notched end of 60 the tube and there a large section, preferably more than half the shaft, is cut away so as to provide a fin or finger, 5, having sharp cutting edges, 6, 6, or at least one sharp cutting edge which, when the shaft 65 is revolved, co-operates with one of the sides of the notch 2 to shear off any thread which may have been laid across the end of the tube in the notches.

The members 1 and 4 are both preferably 70 made of hardened material of a kind which will produce a most satisfactory shearing device.

The tube is rigidly held in place against the frame of the machine, to which it is attached, by means of a suitable clamp, 7, which is so positioned that the shearing end of the cutter will be brought in proximity to the point at which the work leaves the machine. The shaft 4 is preferably supported in a suitable bearing, 8, forming part of or attached to the frame of the sewing machine; there being on the end of the shaft a wheel or pulley, 9, by means of which it may be driven.

If desired, a guide plate, 10, having curved converging lips, 11, may be secured in proximity to the shearing end of the cutter for the purpose of forming a wide mouthed opening or channel into which 90 the thread may be brought and guided positively into the notches in the cutter; thus making it unnecessary to give the same amount of attention to the manipulation of the thread to be cut that would be required 95 if the thread were inserted directly into the notches.

While I have illustrated and described with particularity only a single preferred form of my invention, I do not desire to be 100 limited to the exact structural details thus illustrated and described; but intend to cover all forms and arrangements which come within the terms employed in the definitions of my invention constituting the ap- 105 pended claims.

I claim:

1. A cutter comprising a tube having a notch cut in one end thereof, a shaft fitting revolubly into the tube and projecting into 110

proximity to the end containing the notch, one side of the shaft at the end in the vicinity of the notch being cut away to form a shearing edge adapted to coöperate with the notch.

2. A cutter comprising a tube having notches cut into one end thereof at diametrically opposed points, a shaft fitting revolvably into the tube and provided with a part 10 having a shearing edge arranged within the notched part of the tube and adapted to coöperate with one of the edges of one of said notches to sever a thread extending across

the end of the tube and lying in said notches.

3. A cutter comprising a tube having a notch cut in one end thereof, a shaft fitting revolvably into the tube and provided with a part 15 having a shearing edge arranged within the notched end of the tube and adapted to coöperate with one of the edges of said notch to sever a thread lying in said notch.

In testimony whereof I sign this specification.

GEORGE HOEPNER.

Copies of this patent may be obtained for five cents each, by addressing the "Commissioner of Patents, Washington, D. C."
